UNITED STATES PATENT OFFICE

JOHN ELLIS OSTLINE, OF LIVERPOOL, ENGLAND, ASSIGNOR TO ASSOCIATED TELEPHONE AND TELEGRAPH COMPANY, OF KANSAS CITY, MISSOURI, A CORPORATION OF DELAWARE

TELEPHONE SYSTEM

Application filed September 28, 1927, Serial No. 222,456, and in Great Britain October 14, 1926.

The present invention relates to telephone systems and is more particularly concerned with what is known as routine testing apparatus, that is to say apparatus arranged to 5 reproduce automatically the actual conditions of use for each unit in turn of a large group of similar pieces of apparatus. Moreover the invention while not definitely limited thereto is more specially applicable to the 10 testing of so-called first code selectors which may be broadly defined as first numerical switches in a system employing register controllers. In such a system a first code selector is taken into use over an individual line 15 switch when a subscriber calls and thereupon temporarily associates with itself a register controller adapted to respond to the impulses dialled by the calling party. In due course the register controller sends out correspond- 20 ing trains of impulses, the first series serving to operate the first code selector, and when the connection has been completely set up the register controller is released. Such a first code selector is therefore considerably 25 more complicated than a simple selector switch, and the routine tests must include some arrangements for testing also the apparatus for associating the register controller with the connection. It is the object of the 30 invention to produce routine testing equipment which shall satisfactorily perform all the functions outlined above, though it will be understood that certain of the principles involved can equally well be applied to the 35 testing of other kinds of apparatus.

The testing equipment may conveniently be divided into two parts, firstly the testing apparatus proper, and secondly the distributing switches by means of which the testing apparatus is associated with the particular piece of apparatus it is desired to test. In some circumstances it may be desirable to provide facilities for testing the apparatus manually as well as automatically, and in such a case it is preferable to employ the same distributing equipment for connecting with both the manual and automatic testing equipment. According to one feature of the invention therefore, the various pieces of apparatus are adapted to be associated in turn

with automatic testing apparatus over distributing switches, while means are also provided whereby the pieces of apparatus may also be associated over the distributing switches with manual testing equipment.

In systems of the kind referred to, inasmuch as register controllers should normally only be associated with any one connection for a relatively short period of time, and furthermore since they are comparatively expensive, it is desirable that means shall be provided for releasing a register controller in case it becomes associated with a line but is not used, as may be brought about for instance by a fault on the line. According to another feature of the invention, therefore, in a testing arrangement for the routine testing of apparatus arranged to effect the temporary association of other apparatus therewith, which other apparatus is arranged to be automatically released if held for more than a predetermined time, one of the tests consists in the seizing and holding of a piece of apparatus sufficiently long to test the forced release feature.

A further feature of the invention is that in a testing arrangement for the routine testing of apparatus which is equally available from the routining equipment and from its normal means of access, when a particular piece of apparatus is to be completely routined a plurality of times in succession, special means only operable on continuous routine tests are provided in the routiner for busying the apparatus to prevent its being seized for use while the routiner is preparing for the succeeding test thereon.

These features and a number of subordinate features not specifically mentioned at this point will be better understood from the following description of a preferred method of carrying the invention into effect reference being had to the accompanying drawings. This arrangement has been particularly designed to test first code selectors of the type described in British Patent No. 264,557, but it will be understood that it is not limited to use with first code selectors of this type since the principles involved are capable of considerably wider application.

In a 10,000 line exchange, for which the routiner about to be described is intended to serve, there will probably be from 1,000 to 1,500 first code selectors, and in accordance with the usual practice these will be arranged in shelves each containing 20 switches. For convenience in cabling it is desirable that access should be obtained from one particular switch to the 20 switches comprising a shelf. Conveniently therefore the distributing arrangements comprise a number of secondary distributors equal to the number of shelves of first code selectors and a number of primary distributors sufficient to give access to all the secondary distributors. Preferably also the primary distributors are arranged to be connected in tandem over their 25th contacts, that is to say the first primary distributor will have its wipers directly associated with the routining equipment and the first 24 contacts in its bank will extend to secondary distributors. The 25th set of contacts however will extend to the wipers of the succeeding primary distributor which is wired in a similar manner. The switches associated with the first code selectors for selecting an idle register controller, sometimes known as "A" digit selectors, are preferably of the homing type and the contacts engaged by the line and pulsing wipers in normal position are wired to the routiner and are made use of in carrying out manual tests as will be described subsequently. For the sake of convenience there is provided on each first code selector board a 10-point jack connected through to the routiner. All these jacks are multiplied together and any one can be used for effecting manual tests so that it is possible for the attendant to carry out tests from a position in which he can observe the actual operation of the first code selector. A connection also extends back to the routiner from a vacant level in an exchange selector and over this line circuit changes may be effected corresponding to the reply of a called party.

Referring to the drawings, Fig. 1 shows three eight level primary distributor switches, SW¹, SW², SW³, and one secondary six level distributor switch SW⁴.

Fig. 2 shows the fault indicating lamps FL, together with lamps BSL for indicating the bay and shelf of a particular switch being routined and switch lamps SL which indicate the particular switch under test. This figure also shows the control keys and two time check relays TC¹ and TC².

Fig. 3 shows the routiner impulse sending switch SS, together with the vibrator V employed for generating impulses.

Fig. 4 shows the release timing switch RT which is employed to check the time of release of the switches under test.

Fig. 5 shows the test control switch TC which controls the tests applied to the various switches.

Fig. 6 shows the test switch TS which is employed for altering the connections of the various conductors extending by way of the distributor switches from the switch under test.

In the arrangement shown in Fig. 1, access may be had to as many as 1440 first code switches. The primary distributors SW¹, SW² and SW³ are 25 point switches, and each have access to 24 secondary distributors, while the secondary distributors each have access to 20 first code switches. All the switches SW¹, SW², SW³, SW⁴, SS, RT, TC and TS are of the homing type and advance their wipers one step on release of their operating magnets.

A description will be first given of a successful routine test of a group of first code selectors. In order to set the routine apparatus shown in operation, the exchange attendant operates the automatic routine start key AS, Fig. 2, which completes the following circuit for start relay ST, Fig. 3—battery, relay ST, conductor 10, cable C¹, conductor 10, start key spring AS¹, to earth. The start key AS also sets a time pulse mechanism (not shown) in operation, which is arranged to connect impulses at the rate of 40 per minute (.75 seconds on and .75 seconds off) to conductor PC¹, Fig. 6; 20 impulses per minute at the rate of 1 second on and 2 seconds off, to conductor PC², and 20 per second continuous to conductor PC³. At ST² and ST³, relay ST prepares a testing circuit, which extends from battery, upper winding of relay TT, Fig. 6, normally closed contacts controlled by armature TL², conductor 11, cable C⁴, conductor 11, Fig. 2, junction test key springs 4, resistance r¹ junction test key springs 2, conductor 12, cable C¹, conductor 13, ST², negative terminal 14, which with its associated positive terminal 15 is connected to a spare level of an exchange selector. The positive terminal 15 extends over springs ST³, conductor 18, cable C¹, conductor 18, junction test key springs 1, resistance r², resistance r³, cable C⁴, conductor 18, Fig. 6, normally closed contacts controlled by armature TR¹, lower winding of relay TT, conductor 19, cable C²², conductor 19, Fig. 5, armature TG⁵ to earth. Relay ST at ST⁴ prepares a circuit for testing whether the switch is engaged or its position on the shelf unequipped, by connecting earth to conductor 20, cable C¹⁷, conductor 20, resistance R¹, R², battery. Relay ST at ST⁵ prepares a circuit for two-step relay DS; at ST⁶ prepares a circuit for the driving magnet DM¹ of the primary distributor switch SW¹, Fig. 1; at ST⁷ connects earth impulses at the rate of 40 per minute to relay DQ over the circuit; pulse conductor PC¹, Fig. 6, cable C²³, conductor 22, PM¹, conductor 23, cable C¹⁸, conductor 23, ST⁷, conductor 24, DQ¹, conductor 24, DB¹, conductor 25, lower winding

of DQ to battery. Relay DQ is a two-step relay and at this time only operates its springs DQ², thereby circuiting its upper winding to earth at ST⁸. When the first pulse is removed from the pulse conductor PC¹, Fig. 6, relay DQ operates fully over both its windings in series and locks up at DQ² to earth at ST⁸. Relay ST also at ST¹ energizes relay SS. Relay SS at SS¹, SS², SS³, SS⁴, SS⁵ and SS⁶ disconnects the homing circuits for the primary distributors SW¹, SW² and SW³, at SS⁷ completes the following circuit for relays HA and HB; earth, SS⁷, conductor 26, cable C¹⁶, conductor 26, relay HA and relay HB in parallel to battery, and at SS⁸ prepares a circuit for relay DE, which will be described later.

The next pulse over conductor PC¹ operates relay DR, Fig. 3 as follows: relay DR, conductor 27, DQ¹, conductor 24, ST⁷ and the previously traced circuit to pulse conductor PC¹, Fig. 6. Relay DR completes a circuit for relay DS as follows: earth, DR¹, conductor 28, ST⁵, conductor 29, DS¹, conductor 30, lower winding of relay DS to battery. Relay DS is a two-step relay, and at this time only operates its springs DS², thereby short-circuiting its upper winding to earth at DT¹. Relay DR also completes at DR² a circuit for relay DT as follows: battery, DT, conductor 31, normally closed contacts controlled by DT², conductor 32, DR², conductor 33, cable C¹⁶, conductor 33, normally closed contacts controlled by LS¹, conductor 59, start key springs AS² to earth. At the end of the earth impulses over conductor PC¹, Fig. 6 the circuit of relay DR is opened, and relay DB restores. The initial energizing earth to relay DS is removed, and relay DS operates fully over both its windings in series and locks up to earth at DT¹.

The next earth pulse operates relay DR again, which completes at DR³ the following circuit for magnet DM⁴ of the secondary distributor switch SW⁴; earth, DR³, conductor 35, DS³, conductor 36, DB², conductor 37, cable C¹⁸, conductor 37, Fig. 5, CR¹, conductor 38, cable C²⁶, conductor 38, Fig. 6, MB⁵, conductor 39, SB², conductor 40, SA², conductor 41, cable C⁶, conductor 41, Fig. 1, wiper 7 of primary distributor switch SW¹, first bank contact, conductor 42, driving magnet DM⁴ of secondary distributor switch SW⁴ to battery. Magnet DM⁴ is operated and attracts its armature preparatory to advancing the switch wipers which, as previously mentioned, are advanced upon the release of the operating magnet. Relay DR also completes at DR³ the following circuit for relay DB, Fig. 3: earth, DR³, conductor 35, DS³, conductor 36, DB³, conductor 43, upper winding of relay DB to battery. Relay DB is a two-step relay, and at this time only operates its springs DB⁴, thereby short-circuiting its lower winding to earth

at TM¹, Fig. 5, as follows: earth, TM¹, conductor 44, cable C¹⁷, conductor 44, DS⁴, conductor 45, DB⁴, conductor 46 to relay DB. At the end of the earth pulse, relay DR restores and opens the circuit of magnet DM⁴, 70 which releases and advances its switch wipers to their second bank contacts, relay DR also removes the initial energizing earth for relay DB, and relay DB now locks up over both its windings in series from earth at TM¹ over the circuit previously traced. Relay DB in operating opens at DB² the impulsing circuit to magnet DM⁴ of the secondary distributor switch SW⁴; at DB¹ opens the circuit of relay DQ, which restores; at DB⁵ completes the 75 following circuit for relay DC, Fig. 3: earth, DB⁵, conductor 46, relay DC to battery, and at DB³ relay DB opens its own initial energizing circuit. Relay DQ in releasing opens the pulsing circuit for relay DR. 80

Relay HA, Fig. 4, which was operated by relay SS, at HA¹ to HA¹⁰ inclusive, and relay HB, which was operated at the same time, at HB¹ to HB¹⁰ inclusive, disconnects the homing earth from the private bank P 90 of the secondary switch SW⁴.

When relay ST operated as a result of the operation of the automatic start key AS, the following circuit is completed for the appropriate bay and shelf lamp, Fig. 2: earth, ST¹, conductor 47, cable C¹⁸, conductor 47, cable C²⁶, conductor 47, SB¹, conductor 48, SA¹, conductor 49, cable C⁶, conductor 49, wiper 8, primary distributor SW¹, bank contact 1, conductor 50, cable C¹¹, conductor 50, lamp 1, shelf AB to battery, Fig. 2. 95

When the secondary distributor switch SW⁴, Fig. 1, advanced its private wiper P into engagement with the second bank contact as a result of its magnet DM⁴ de-energizing, the following circuit was completed for a switch lamp SL¹, Fig. 2 in series with relay LP, Fig. 4: earth, relay LP, Fig. 4, conductor 51, lamp SL¹, Fig. 2, conductor 52, cable C⁹, conductor 52, bank contact 2 of switch SW⁴, wiper P, conductor 53, interrupter contacts IS⁴, magnet DM⁴ to battery. Relay LP operates in this circuit, and lamp 1 glows, but magnet DM⁴ does not operate due to the resistance of lamp SL¹. Relay LP 110 upon operating completes a circuit from earth, LP¹, conductor 54, for relay LS. Relay LS upon operating, at LS¹ completes the following circuit for relay DE, Fig. 3: battery, upper winding of relay DE, conductor 55, cable C¹⁶, conductor 55, LS², conductor 56, cable C¹⁶, conductor 56, DB⁵ to earth. Relay DE upon operating completes the following locking circuit: earth, SS², conductor 57, DE², lower winding of DE to battery. Relay 115 LS in operating, at the normally closed contacts controlled by armature LS¹ opens the circuit of relay DT, which de-energizes. Relay DS which was previously maintained by DT does not release, since contacts LS¹ 120

125

130

135

complete an alternative holding circuit as follows: battery, lower and upper windings of relay DS in series, DS², conductor 58, cable C¹⁶, conductor 58, Fig. 4, LS¹, conductor 59, automatic start key springs AS² to earth. 5 Relay DE at springs DE¹ prepares a circuit for the primary distributor magnet DM¹, Fig. 1. Relay DC, Fig. 3, upon operating prepares a circuit at springs DC³ for two-step relay PT, and at the same contacts removes earth from the homing bank of the sending switch SS, Fig. 3, at springs DC² prepares a locking circuit for relay PA, at DC⁵ removes earth from conductor 60, which 10 extends over cable C¹⁹, conductor 60, Fig. 6, and from the homing bank P¹ of the test switch TS, and at DC⁴ completes a circuit for the holding coil of the routine time check relay TC² as follows: battery, holding coil 15 of time check relay TC², resistance r⁹, conductor 61, cable C¹⁴, conductor 61, Fig. 4, PU², conductor 62, cable C¹⁶, conductor 62, Fig. 3 to earth at DC⁴. Moreover at DC¹ relay DC removes earth from the private bank P of the test control switch TC, Fig. 5 as follows: earth DC¹, conductor 63, cable C¹⁷, conductor 63, Fig. 5, and at this same armature completes the following circuit for relay TK, Fig. 5: battery, winding of relay 20 TK, first bank contact in level 3 of test control switch TC and its associated wiper, conductor 64, cable C², conductor 64, Fig. 2, springs 1 of reset key RS, conductor 65, cable C¹, conductor 65, Fig. 3 to earth at DC¹. A 25 branch of this circuit extends over conductor 66, Fig. 3, cable C¹⁷ to conductor 66, Fig. 5, wiper 2 and first contact of the test control switch TC, conductor 67, cable C²⁷ to conductor 67, Fig. 2, fault lamp 1 to battery. 30 Fault lamp 1 upon lighting indicates to the attendant that the routining operation has commenced on the switch indicated by the previously lighted bay, shelf and switch indicating lamps. 35 Relay TK at TK¹ earths the first bank contact with which wiper 4 of test control switch TC is in engagement, and operates magnet DM⁷ via its interrupter springs and causes the switch TC to advance its wipers one step. 40 At the same time relay TK at TK¹ completes the following circuit for relay PU, Fig. 4: earth, TK¹, first bank contact of wiper 4 of switch TC, conductor 68, cable C²⁰, conductor 68, Fig. 4 and winding of relay PU to battery. 45 Referring now to the time check relays TC¹ and TC², Fig. 2, it will be remembered that the holding coil of TC² was energized by the operation of relay DC. The stepping winding of the time check relay TC² is at this time 50 receiving impulses at the rate of 40 per minute over conductor 69, cable C¹⁴, conductor 69, Figure 4, PU¹, conductor 70, cable C¹⁶, conductor 70, Figure 3, ST⁷ conductor 23, cable C¹⁶, conductor 23, Figure 4, PM¹, conductor 22, cable C²³ to pulse conductor

PC¹, Figure 6. The object of these time check relays which are of known construction is to delay the sounding of an alarm in the exchange following a fault indication, since a switch may be only temporarily busy but in the case of a permanent fault, an alarm will be sounded after a three-minute interval. Moreover some of the tests require an appreciable time, say half a minute, to complete and it is therefore essential to have some means of delaying the sounding of the fault alarm. The time check relay TC² provides the necessary time interval during the routining operation and the time check relay TC¹ provides a similar interval during the release of the routine. 70 75 80

Considering now the operation of PU, when this relay operates it disconnects at springs PU¹ and PU² the holding and stepping circuits to the routine time check relay TC², Figure 2. When the test control switch TC, Figure 5 advances its wipers into engagement with the next set of bank contacts, it will disconnect the energizing circuit for relay PU and PU will accordingly release and prepare the time check circuits again. At this time earth potential is connected to wipers 2 and 3 of the switch TC as previously described and therefore when the switch advances to the second bank contact the following circuit will be completed for slow release relay TN Figure 5: battery, relay TN, second bank contact in level 3 and its associated wiring to earth at DC¹ Figure 3. As previously stated the stepping magnet DM⁷ of the test control switch TC is connected via its own interrupter contacts to the wiper of level 4 and if this wiper is resting on a bank contact to which earth potential is connected the switch will automatically advance one step and connect up a different testing condition. Relay PU, Figure 4, is also operated in parallel with magnet DM⁷ over conductor 68 in order to disconnect the time check relay TC² and allow it to restore. With the wipers switch TC in engagement with the second bank contact the following circuit is completed from level 2 for fault lamp FL², Figure 2: lamp FL², conductor 71, cable C²⁷, conductor 71, Figure 5, second bank contact in level 2 and its associated wiper to earth at DC¹, Figure 3. The lighting of the lamp FL², Figure 2, indicates that the switch under test is busy, either because it is in use or because of a fault. 100 105 110 115 120

In order to produce a different operation of the routiner according as a switch is busy or the corresponding position is unequipped on the shelf, polarized relays PN and PP are provided. When a switch is busy, the release trunk conductor will be earthed. Assuming that the release trunk conductor connected to the second bank contact of wiper 3 of the secondary distributor SW⁴, Figure 4, is earthed, the following circuit is completed for 125 130 135 140

relay PP, Figure 5: earth on release trunk conductor connected to the second bank contact of level 3 of switch SW⁴, Figure 1, and its associated wiper, conductor 72, first bank contact in level 4 of switch SW¹ and its associated wiper, conductor 73, cable C⁶, conductor 73, Fig. 6, SA⁴, SB⁴, MB³, conductor 74, cable C²⁴, conductor 74, Fig. 4, CB⁸, conductor 75, cable C²⁴ conductor 75, Fig. 5, to wiper of level 4 of the test switch, Fig. 6, and its first bank contact, conductor 76, cable C⁴, conductor 76, Fig. 2, normally closed contacts of private disconnect key PDK, conductor 77, cable C², conductor 77, Fig. 5; TR¹, winding of the polarized relay PP, winding of polarized relay PN to the junction of resistances R¹ and R² the opposite ends of which are connected to earth and battery respectively. In this circuit only relay PP operates and completes a circuit at PP¹ for relay TR. Relay TR upon operating completes a locking circuit for itself at contacts TR² to earth on the release trunk conductor of the switch under test. At TR¹ relay TR disconnects the polarized relay PP which now restores and at TR³ removes stepping earth from the second bank contact in level 4 of switch TC and also from the conductor 78, which is connected to first bank contact of the level P¹ of the test switch TS over conductor 78 and cable C²². This condition now persists until either the switch under test becomes free or the exchange attendant advances the routiner on to another switch after receiving the alarm and ascertaining that the switch is held up by a subscriber or is busy as the result of a fault.

If however the switch position is unequipped, battery potential will be connected to the release trunk conductor of the unequipped position and relay PN will operate instead of relay PP and at PN¹ complete a circuit for relay TM. Relay TM upon operating removes earth at TM¹ from conductor 44 and releases relay DB. Relay DB upon releasing reconnects relay DQ to the pulsing conductor PC¹ whereupon the secondary distributor SW⁴ is advanced one step.

It may be mentioned at this point that if a key is provided which will disconnect DB and also the pulse conductor PC¹, the attendant can advance the routiner on to another switch in the case of an alarm being given as the result of a fault or a prolonged busy condition. In the arrangement shown however the attendant can advance the routiner on to another first code selector by operating the continuous routine key CRK, Fig. 2, releasing the automatic start key AS and operating the secondary distributor stepping key SDSK, and then reoperating the automatic start key AS and releasing the continuous routine key.

Assuming now that the first code selector engaged by the secondary distributor switch

SW⁴, Fig. 1, becomes free before the three minute time alarm becomes operative, everything is ready for the start of the routining operation.

When the switch becomes free, earth is removed from the release trunk conductor and relay TR, Fig. 5, will release and complete stepping circuits for the test control switch TC and the test switch TS. Relay TR upon releasing operates the test switch TS by connecting earth to the driving magnet DM⁸ over the following circuit: earth, TR³, Fig. 5, FN¹, TK², conductor 78, cable C²², conductor 78, Fig. 6, first bank contact of level P¹ and its associated wiper, interrupter springs and magnet DM⁸ to battery. Magnet DM⁸ upon operating advances its associated wipers into engagement with the second set of bank contacts in which position the negative and positive conductors of the first code selector are tested for continuity, contact with each other, or neighbouring conductors and contact with earth or battery potential. The test control switch TC will advance its wipers from second to third contacts in which position it indicates the test being performed by lighting the fault lamp FL³, Fig. 2, over the circuit: battery, lamp 3, conductor 79, cable C²⁷, conductor 79, Fig. 5, third bank contact in level 2 of switch TC and its associated wiper to earth at DC¹, Fig. 3. The negative speaking conductor extends from second bank contacts and level 1 of the secondary distributor SW⁴, first bank contact and level 2 of the primary distributor SW¹, conductor 80, cable C⁶, conductor 80, Fig. 6, SA⁶, SB⁶, MB¹, wiper 2 of switch TS and its second bank contact, conductor 81, cable C⁴, conductor 81, Fig. 2, to spring 2 of the negative test key NTK, conductor 82, cable C², conductor 82, Fig. 5, TG², lower winding of relay TD, TD², windings of relays TP and TA in series to earth.

It should be explained that relays TA and TP are low resistance relays of for instance 1 ohm each, and consequently it is desirable to provide some safeguard in case direct battery potential should be connected through these relays. This is taken care of by making relay TD marginal so that it will only operate over its 2 ohm lower winding when full battery potential is encountered. Relay TD upon operating immediately connects up its high resistance upper winding in series with its lower winding thus reducing the current and preventing the continual blowing of fuses when this condition is encountered.

The positive line conductor is extended to low resistance relays TQ and TB and guard relay TJ as follows: positive speaking conductor, second bank contact and wiper in level 2 of switch SW⁴, first bank contact and wiper in level 3 of switch SW¹, conductor 83, cable C⁶, conductor 83, Fig. 6, SA⁵, SB⁵, MB², wiper of lever 3 of switch TS and its second bank contact, conductor 84, cable C⁴, con-

ductor 84, Fig. 2, spring 2 of the positive test key PTK, conductor 85, cable C², conductor 85, Fig. 5, TG³, upper low resistance winding of relay TJ, TJ², windings of relays 5 TJ and TB in series to battery. Relays TJ and TB are similar to relays TP and TA and relay TJ performs the same function as relay TD.

In the first code selector the positive and 10 negative speaking conductors terminate in a battery feed relay, the positive conductor being connected through one winding to earth, and the negative conductor through the other winding to battery, hence if the line 15 conductors are continuous, relays TA and TB will operate. Relays TP and TJ are marginal, and do not normally operate at this time. The operation of relays TA and TB completes the following circuit for slow-to-pull-up 20 relay TO: earth, TB¹, TJ¹, TJ², TA¹, TP¹, TD¹, relay TO to battery. Relay TO upon operating completes a circuit over the third bank contact in level 1 of switch TC and its 25 associated wiper for the driving magnet DM⁷, which advances the test control switch to the fourth set of bank contacts. At this 30 time fault lamp FL³ is glowing, indicating that the loop test is being applied, and if the test is satisfactory, this lamp will be extinguished when the test control switch advances.

If either of the speaking conductors is disconnected, either relay TA or relay TB will 35 not operate, and the switch will not be advanced. If the negative conductor is in contact with another negative speaking conductor there will be an increased flow of current through the relays TA and TP, and under this condition relay TP also will operate and 40 open the circuit for advancing the switch. If the negative speaking conductor is in contact with a positive speaking conductor, the battery feed relay in the first code switch will be operated over one of its windings, and the 45 release trunk conductor will be earthed by the associated guard relay, and this fault will show up as a busy condition. Should there be a very low resistance earth on the positive line or a direct battery connection on the 50 negative line, then either marginal relay TJ or relay TD will operate, and open up the circuit for advancing the test control switch. In the event of any one of these faults occurring, the test control switch will not be advanced, and the loop test fault lamp T³, Fig. 2 will be glowing, and when the time check relay operates, the attendant will know that the loop test is faulty.

In place of the marginal arrangement with 55 relays TA and TP, two polarized relays could be connected in series across the neutral points of a Wheatstone bridge arrangement, two arms of which each include a winding of the battery feed relay in the first code switch, 60 while the other two arms comprise suitable

balancing resistances. In this case a fault on the negative line would operate one polarized relay, and a fault on the positive line would operate the other polarized relay, and in this arrangement the attendant would know straight away which of the two conductors was making contact.

With the test control switch in fourth position, relays TA, TP and the lower winding of relay TD will be connected to the negative speaking conductor, and relays TB, TJ and the upper winding of relay TJ will be connected to the positive conductor, and the line and release relays of the first code switch will be operated and earth will be applied to the release trunk conductor. Moreover the following circuit is completed for the private guard lamp FL⁴: battery, private guard lamp 4, conductor 86, cable C²⁷, conductor 86, Fig. 5, conductor 86, fourth bank contact and wiper of level 2 of switch TC to earth at BC¹, Fig. 3.

If the operation of the battery feed and guarding relays takes place correctly in the first code selector, the earth on the release trunk conductor will bring about the operation of relay TC, Fig. 4, as follows: battery, relay TC, conductor 87, cable C²⁰, conductor 87, Fig. 5, TN², conductor 88, cable C², conductor 88, Fig. 2, normally closed contacts of private disconnect key PDK, conductor 89, cable C⁴, conductor 89, Fig. 6, second contact and wiper of level 4 of switch TS to the release trunk conductor of the first code selector. Relay TC upon operating at its armature 3 advances the control switch TC one step by completing the following circuit: earth, TC³, conductor 90, cable C²⁰, conductor 90, Fig. 5, fourth bank contact and wiper in level 4 of switch TC to relay PU and also to the driving magnet DM⁷. The switch TC is thus advanced to the fifth bank contact, and relay PU again sets the time check relay TC². Should the guarding earth not be returned over the release trunk conductor of the first code switch, the test control switch TC would not be advanced, and glowing of the lamp FL⁴ when the time check alarm became operative would indicate the nature of the fault.

With the test control switch in position 5, conditions are established to enable the routiner to test the correct operation of the switching relay associated with the A digit switch selector in the switch under test. In British Patent No. 264,557 this relay is designated by K and a connection is made from one side of this relay to a terminal to which wiper 4 of the secondary distributor switch SW⁴ has access. When the first code selector is taken into use, its line and release relays operate and a circuit is completed for setting in operation its associated A digit switch selector. When this switch finds an idle A digit switch, relay K operates and connects up the switch

seized. In order to test the proper operation of relay K, it is necessary to ascertain that earth potential is connected to conductor KR, Fig. 1. With switch TC in 5th position, 5 lamp FL⁵ is lighted over the following circuit: battery, lamp FL⁵, conductor 91, cable C²⁷, conductor 91, 5th bank contact and wiper of level 2 of switch TC to earth at DC¹, Fig. 3. The glowing of this lamp indicates that the 10 K relay test is in progress.

Assuming earth is duly connected to connected to conductor KR, Fig. 1, it will be extended over bank contact and wiper in level 4 of SW⁴, contact 1 and wiper in level 5 of 15 switch SW¹, cable C⁶, conductor 91, Fig. 6, SA³, SB³, MB⁴, wiper and bank contact 2 in level 5 of switch TS, conductor 92, cable C²¹, conductor 92, Fig. 4, TC⁴, conductor 93, cable C²⁰, conductor 93, Fig. 5, winding of 20 relay TE to battery. Relay TE operates and completes a circuit for relay TF at armature 1. Relay TF operates and at TF² earths the 5th bank contact in level 4 of switch TC thereby advancing the switch to the 6th position. 25 The lamp FL⁵ remains alight however due to the 5th and 6th contacts being multipled. Relay TF also at TF¹ prepares a circuit for relay TH.

The circuits remain in this condition until 30 the time pulse relays in the A digit switch operate and bring about the release of the A digit switch. When this happens, earth potential is removed from the KR conductor and relay TE, Fig. 5, releases, thereby completing the following circuit for relay TH; earth, TE¹, TF¹, relay TH to battery. Relay TH upon operating completes a circuit for relay TG at TH¹ and at TH² prepares a circuit for advancing the test switch TS and 35 at TH³ earths the 6th contact in the bank of level 4 of switch TC, thus operating the driving magnet DM⁷ to advance the switch to 7th position. This disconnects the fault lamp FL⁵ and connects up the lamp FL⁶ which indicates that the first code selector is being held on a loop with the A digit switch released. Lamp FL⁶ is lighted over conductor 94, cable C²⁷, the 7th contact in the bank of 40 level 2 of switch TC to earth. When relay 45 TE releases, it opens the circuit of relay TF which also releases and the circuit is now completed for magnet DM⁸ of the test switch TS as follows: earth, TE¹, TF¹, TH², (TH being slow to release holds up for an instant), 50 conductor 95, cable C²², conductor 95, Fig. 6 to the magnet DM⁸ of switch TS. Magnet DM⁸ does not advance the wipers until its circuit is opened at TH² by the falling away of slow 55 relay TH, whereupon the wipers of the switch TS are advanced into engagement with the 3rd set of bank contacts. With 60 relay TG in operated position and TH de-energized, earth is connected to the 7th contact in level 4 of the test control switch TC as follows: earth, TH³, TG⁴, 7th bank contact,

wiper 4 to the driving magnet DM⁷ which accordingly advances the wipers to the 8th position.

In this position lamp FL⁶ is extinguished and lamp FL⁷ is lighted over conductor 95, 70 cable C²⁷, 8th bank contact and wiper of level 2 of the switch TC to earth to indicate that the 1st code selector under test is being released. In the previous test when relay TG operated it opened the loop circuit extending 75 to the first code selector at contacts TG² and TG³ and this operation caused the line and release relays of the first code selector to fall away. When the first code selector releases earth is normally removed from the release 80 trunk conductor of the switch and this leaves the switch free to be seized by any hunting line switch. In order to prevent this occurring, relay TN is operated to place a guarding earth on the release trunk conductor of the 85 first code selector under test. Relay TN is operated from battery, relay TN, bank contacts 7 and 8 of level 3 of switch TC and the associated wiper to earth. Relay TN in operating earths the private lead P, Fig. 1, 90 extending to the release trunk conductor of the first code selector under test from earth. TN², conductor 88, cable C², and thence over the circuit previously traced, thus busying the first code selector to any hunting line 95 switch during the time the first code selector is releasing and until it is again operated by the routiner. When relay TG releases, earth is connected to the 8th bank contact in level 4 of switch TC and the switch is advanced to 9th position. In this position lamp FL⁷ is extinguished and lamp FL⁸ is lighted over conductor 102, cable C²⁷, conductor 102, 9th bank contact in level 2 of switch TC to earth at DC¹, Fig. 3.

Upon the release of relay TG and the movement of the test switch to third position, the following loop is closed across the line conductors of the first code selector under test: negative speaking conductor, second 100 bank contact in level 1 of secondary distributor SW⁴, first bank contact and level 2 of primary distributor SW¹, conductor 80, cable C⁶, conductor 80, Fig. 6, SA³, SB³, MB⁴, wiper and third bank contact in level 2 of 105 switch TS, conductor 98, cable C²¹, conductor 98, PR³, conductor 99, cable C¹⁶, conductor 99, Fig. 3, PE² and PB¹ in parallel, conductor 100, cable C¹⁷, conductor 100, Fig. 5, cable C¹⁷, TG⁶, conductor 101, cable C²², conductor 101 Fig. 6, third bank contact in level 110 3 of test switch TS and associated wiper, to the positive speaking conductor over the previously traced circuit. The line relay of the first code selector energizes over this loop 115 and its associated release relay guards the release trunk. Earth coming back on the release trunk operates TC, Fig. 4, as before which prepares a circuit for relay TE, Fig. 5, which operates when earth is connected to 120 125 130

the switching relay conductor KR, Fig. 1 from the first code selector. Fault lamp FL⁸ indicates that a test is being made of the forced release from a seized register controller.

- 5 In order to gain access to a register controller, it is necessary to transmit a series of impulses to operate the A digit switch which will then take into use an idle register controller.
- 10 With the test control switch in position 9, relay PS, Fig. 3, is operated as follows: battery, relay PS, conductor 96, cable C¹⁷, conductor 96, Fig. 5, bank contact 9 in level 3 of switch TC to earth at DC¹, Fig. 3.
- 15 Relay PS upon operating at PS¹ completes a circuit for PA which upon operating locks up at PA² to earth at DC². Relay PA also completes a circuit at PA¹ for the vibrator V which is employed for transmitting impulses
- 20 at springs V² in known manner, and at PA³ completes a circuit for advancing the control switch TC over the conductor 97, cable C¹⁷, conductor 97, Fig. 5, 9th bank contact in level 4 of switch TC and its associated
- 25 wiper to magnet DM⁷. Magnet DM⁷ operates and advances the switch wiper to the 10th set of bank contacts. In this position lamp FL⁸ is disconnected and lamp FL⁹ lighted over conductor 103; this indicates that the first
- 30 code selector is being held waiting for the forced release to become effective.

Upon the operation of the vibrator V impulses at the rate of 10 per second are produced at contact V² and are transmitted to relay PE as follows: battery, relay PE, PC¹, PD¹, V² to earth at PA¹. Relay PE accordingly impulses at the rate of 10 per second and at springs PE¹ transmits impulses to the sending switch magnet DM⁵. Impulses are also transmitted to the line relay of the first code selector under test by the operation of springs PE². When the sending switch SS advances from normal to second position, a circuit is completed for slow relay PB, and PB upon operating, at PB¹ removes a short-circuit from the impulse springs PE², at PB² prepares a circuit for relay PT, at PB³ prepares a circuit for relay PD, and at PB⁴ prepares a circuit for relay PC.

50 The first operation of impulse springs 2 of relay PE is ineffective, since they are short-circuited by springs 1 of relay PB. The second interruption of springs 2 of relay PE effects the transmission of an impulse to the line relay of the first code selector over conductors 99 and 100 and the previously traced circuit to the windings of the first code selector line relay. A second impulse is transmitted in a similar manner and the sending switch is advanced from third position to fourth. In this position of the sending switch SS the following circuit is completed for stop relay PC: earth, wiper and 4th bank contact in level 2 of switch SS, PB⁴, winding of stop relay PC to battery. Relay PC

upon energizing opens the circuit of PE at PC¹ and thus prevents further impulses from the vibrator contacts V² from becoming effective. Relay PC also at PC² opens the locking circuit for relay PA which releases and stops

70

the vibrator. The first code selector line relay repeats these two impulses to the A digit switch which has been associated therewith and this switch steps up to the second level and selects an idle register controller. When the first code selector is connected to an idle A digit switch, earth is connected to conductor KR, Fig. 1, and this potential operates relay TE as before and relay TE operates relay TF. Relay TF upon operating prepares a circuit for relay TH as previously described. Since no further impulses are transmitted to the register controller its own forced release control will become operative in due course and earth will be removed from the conductor KR, Fig. 1, and relay TE will release. Relay TE upon releasing operates relay TH and releases relay TF. With relay TH operated, earth is connected to the 10th contact in bank 4 of the test control switch TC and the driving magnet DM⁷ advances the wipers of this switch to the 11th position. In this position lamp FL⁹ is extinguished and lamp FL¹⁰ lighted over conductor 104. The lighting of lamp FL¹⁰ indicates that the forced release from the register controller has taken place satisfactorily and that the first code selector is held in a loop circuit. When relay TF releases, it completes a circuit for the magnet DM⁸ of the test switch TS, whereupon magnet DM⁸ energizes but does not advance the wipers until TH releases. Relay TH also opens the circuit of relay TG which removes the loop circuit which is holding the first code selector. By the release of magnet DM⁸ the wipers of the test switch TS are advanced from the third to the fourth set of bank contacts. With the switch TS in fourth position, circuits are prepared for connecting a resistance in series with the loop extending to the first code selector in order that marginal operation of the relays of that switch may be tested. Furthermore in this position meter lead M, Fig. 1, is extended to relay TY in order to permit the metering operation to be subsequently checked.

95

When relay TH released it completed a circuit over TH², TG⁴, 11th bank contact in level 4 of switch TC to the magnet DM⁷, which accordingly advances the wipers from the 11th position to the 12th position. In this position lamp FL¹⁰ will be extinguished and lamp FL¹¹ lighted over conductor 105. When relay TG releases, another circuit is completed for advancing the switch TC over bank contact 12 in level 4 of switch TC to the magnet DM⁷ and the wipers are advanced from the 12th position to the 13th position and lamp FL¹¹ is extinguished and lamp

110

115

120

125

130

FL¹² lighted over conductor 106. When wiper 3 of switch TC is in engagement with the 11th bank contact, it completes a circuit for relay TN, which upon operating, feeds 5 guarding earth back to the conductor P, Fig. 1, as previously described. Relay TN remains operated when the switch advances from its 11th to 12th position in order to maintain the release trunk guarded during 10 this interval. The lighting of lamp FL¹² indicates that the impulsive test is being applied to the first code selector. When relay TG released it again completed a loop circuit to the first code selector, resistance 115, Fig. 15 3 being now included in series with the loop as follows: conductor 100, Fig. 3, cable C¹⁷, conductor 100, TG⁶, conductor 116, cable C¹⁷, conductor 116, Fig. 3, series resistance 115, PT⁴, conductor 117, cable C¹⁹, conductor 117, Fig. 6, 4th bank contact in level 3 of test 20 switch TS and associated wiper, MB², SB⁵, SA⁵, conductor 83, Fig. 1, cable C⁶, wiper and bank contact in level 3 of switch SW¹, wiper and bank contact in level 3 of switch SW⁴ 25 to the positive speaking conductor. The other side of the loop extends to the negative speaking conductor over the same circuit as previously described. Due to this loop the line relay in the first code selector is re-operated through the high resistance 115.

In order to check that the line relay responds properly to impulses through this resistance, the digits 666 are transmitted to the first code selector by which they are repeated to a register controller. In the 13th position of switch TC, relay PS, Fig. 3 is operated over conductor 96. Relay PS will operate PA again and relay PA will start up the vibrator V and relay PE will start 30 impulsing over the loop as previously described. The sending switch SS in passing from contacts 4 to 11 will send six impulses before relay PD is operated. Relay PA in operating places earth on the 13th bank 35 contact in level 4 of switch TC and driving magnet DM⁷ advances the wipers of the switch to the 14th position. In this position lamp FL¹² is extinguished and lamp FL¹³ is lighted over conductor 108, thus indicating 40 that the register controller is in a condition to respond to digits repeated from the first code selector. Relay TU is operated when the test control switch is standing in the 14th position in order to place a shunt resistance 45 across the loop circuit for the first code selector in order to test the impulsing of the line relay of the switch under these conditions. Relay TU operates from battery, winding of relay TU, 14th bank contact in level 3 50 of switch TC and associated wiper to earth at DC¹. Relay TU at TU¹ closes a circuit to relay TV which operates, and TU² prepares the shunt resistance circuit which will be traced later. Relay PD is operated from 55 battery, winding of relay PD, Fig. 3, PB³,

bank contact 11 in level 2 of sending switch SS and associated wiper to earth. Relay PD at PD¹ disconnects relay PE which releases in order to prevent further impulses being sent to the first code selector under test, and 60 at PD² completes a circuit for two-step relay PT from earth, PB², PD², PT², upper winding for PT to battery. Relay PT at this time only closes contacts PT³ short-circuiting its lower winding to earth at DC³. When the 65 sending switch SS moves from position 10 to position 11 the circuit of slow release relay PB is opened and relay PB releases, and at PB² removes the initial energizing earth from relay PT which operates fully from earth, 70 PC³, PT³, windings of relay PT in series to battery, at relay PT² opens its initial energizing circuit and at PT⁴ removes the series resistance 115 from the loop to the negative 75 and positive speaking conductors and at PT¹ closes the shunt resistance circuit across the speaking conductors as follows: negative speaking conductor, second bank contact and wiper in level 1 of secondary distributor 80 switch SW⁴, Fig. 1, first bank contact and wiper in level 2 of primary distributor switch SW¹, conductor 80, cable C⁶, conductor 80, Fig. 6, SA⁶, SB⁶, MB¹, wiper and 4th bank contact in level 2 of test switch TS, conductor 85 90 95 98, cable C²¹, conductor 98, Fig. 4, PR³, conductor 99, cable C¹⁶, conductor 99, Fig. 3, PE² and PB¹ in parallel, conductor 100, cable C¹⁷, conductor 100, Fig. 5, TG⁶, conductor 116, cable C¹⁷, conductor 116, Fig. 3, PT⁴, conductor 117, cable C¹⁹, conductor 117, Fig. 6, 100 4th bank contact and wiper in level 3 of test switch TS, MB², SB⁵, SA⁵, conductor 83, positive speaking conductor. The shunt resistance is placed across the loop from conductor 100, resistance 118, PT¹, conductor 119, cable C¹⁷, conductor 119, Fig. 5, TU², conductor 120, cable C²⁰, conductor 120, Fig. 4, to PR³. PB upon releasing, at PB² opens the 105 circuit of relay PD which releases, and at PB¹ short-circuits the impulsing springs of relay PE in order to render these ineffective. Relay PD in releasing at PD¹ completes the circuit to relay PE which will start impulsing over the loop as previously described. 110 Sending switch SS, Fig. 3, will now be moved from position 14 to position 20 and will send out six impulses before relay PD is again operated in the manner previously described. Relay PD in operating disconnects relay PE which releases and prevents further impulses being delivered to the first code selector. 115 Sending switch SS in passing from position 20 to position 21 opens the circuit of relay PB which releases and opens a circuit for relay PD which also releases after an interval. 120 PD in releasing closes a circuit to relay PE which will start impulsing over loop as previously described. Sending switch SS will now move from position 21 to position 25 and six further impulses will be delivered to the 125 130

loop circuit of the first code selector under test before relay PC is operated as before described. Relay PC at PC¹ disconnects relay PE to terminate impulse sending and at PC² opens the circuit of relay PA which releases and disconnects vibrator V. Sender switch SS in passing from position 24 to position 25 opens the circuit of relay PB which releases and opens the circuit of relay PC which releases also.

In this manner, three series of six impulses have been delivered to the first code selector, the first or A digit being received by the A digit switch and the second and third or B and C digits by the register controller which is selected from the 6th level of the A digit switch. The register controller is now caused to send out series of impulses which will route the connection from the first 20 code selector under test through suitable exchange selectors to the vacant local selector level which is connected back to the routiner. The register controller and A digit switch will then be disconnected from the switch 25 train leaving the wipers of the first code selector switch connected through to terminals 14 and 15 and thence to relay TT. This circuit extends from battery, upper winding of relay TT, Fig. 6, normally closed contacts 30 controlled by armature TL², conductor 11, cable C⁴, conductor 11, Fig. 2, junction test key springs JT⁴, resistance r⁴, junction test key springs JT², conductor 12, cable C¹, conductor 13, ST², negative terminal 14, back 35 bridge in first code selector, positive terminal 15, ST³, conductor 18, cable C¹, conductor 18, junction test key springs JT¹, resistance r², resistance r³, cable C⁴, conductor 18, Fig. 6, normally closed contacts controlled by armature TL¹, lower winding of relay TT, conductor 19, cable C², conductor 19, Fig. 5, armature TG⁵ to earth. This circuit is of course only completed if the line relay of the first code selector has correctly repeated 40 the digits 666 sent under varying line conditions. Relay TT in operating at TT¹ completes the circuit: earth, conductor 121, cable C²², conductor 121, Fig. 5, 14th bank contact in level of the test control switch, magnet 45 DM⁷ to battery whereupon the wipers are advanced to the 15th position. In this position lamp FL¹⁴ is lighted over conductor 108 to indicate that the holding feature of the first code selector is under test. The control switch TC in passing from contacts 14 to position 15 opens the circuit of relay TU which releases and opens the circuit of the relay DB. The test control switch TC in position 15 completes a circuit for relay TG; 50 battery, winding of TG, conductor 122, 15th bank contact in level 3 of the switch TC and associated wiper to earth at DC¹. Relay TG in operating, at TG⁵ removes earth from lower winding of relay TT and replaces 55 it by battery through resistance 123, and at

TG⁶ opens the circuit to the first code selector under test. This condition is equivalent to the holding condition on a call to an operator's position when the calling subscriber opens the calling loop by hanging up his receiver or to the silent period during busy flash. This condition persists until slow relay TV releases and during this time earth should be maintained on the release trunk conductor in order to guard that switch from 60 intrusion. When relay TV falls away, earth is supplied to bank contact 15 of the test control switch TC over conductor 124, TV², conductor 90, cable C²⁰, conductor 90 and TC³. Driving magnet DM⁷ of the test control switch operates and advances the wipers to the 16th position. Should earth for any reason be removed from the release trunk conductor during this period, relay TC would release and at TC⁸ remove stepping earth 65 thereby preventing the advance of the switch TC. The test control switch TC in passing from position 15 to 16 opens the circuit of relay TG which releases and at TG¹ closes the circuit of relay TU; battery, winding of 70 relay TU, conductor 125, TG¹, conductor 126, 16th bank contact and wiper in level 3 of the test control switch TC to earth at DC¹. Relay TU operates and at TU¹ completes a circuit for relay TV which operates also. Relay TV in operating at TV³ connects earth to contact 16 in level 4 of the test control switch TC and the driving magnet DM⁷ advances the wipers of the test switch from the 16th to the 17th position. In moving 75 from position 16 to position 17 the switch TC opens the circuit of the relay TU which releases and opens the circuit of relay TV. The switch TC also extinguishes fault lamp FL¹⁴ and lights fault lamp FL¹⁵ over conductor 109 in order to indicate that the test of the metering operation is being conducted. Relay TV in releasing closes a circuit for relay TL; battery, winding of relay TL, Fig. 6, conductor 127, cable C²², conductor 127, Fig. 5, TV¹, a conductor 128, bank contact 17 and wiper of level 3 of the switch TC to earth at DC¹. Relay TL in operating at 80 TL¹ and TL² reverses the connection of the windings of relay TT to the back bridge at the first code selector. This reverses the direction of the current flowing through the polarized relay at the first code selector whereupon this relay should operate to initiate metering. This will result in the connection of earth to lead M, Fig. 1, whence it is extended over bank contact 2 and level 2 of secondary distributor SW⁴, first bank contact and wiper in level 6 of the primary distributor SW¹, conductor 129, cable C⁶, conductor 129, Fig. 6, SA⁷, SB⁷, MB⁶, conductor 130, wiper and 4th bank contact in level 6 of the test switch TS, Fig. 6, conductor 131, cable C⁴, conductor 131, Fig. 2, normally 85 closed contact of the meter fail key MFK, 130

Fig. 2, conductor 132, cable C⁴, conductor 132, Fig. 6, relay TY to battery. The operation of relay TY at TY¹ earths the 17th bank contact in level 4 of the test control switch by way of conductor 133, cable C²², conductor 133, Fig. 5, 17th bank contact in level 4 of the test switch TC, Fig. 5, whereupon the driving magnet DM⁷ advances the wipers of the test switch to the 18th position.

In this position of the test control switch a test is made of the release time of the first code selector after the calling loop has been opened. The switch TC in moving from position 17 to 18 extinguishes lamp FL¹⁵ and lights lamp FL¹⁶ over conductor 110. Relay PR is now operated from battery, winding of relay PR, Fig. 4, conductor 134, cable C²⁰, conductor 134, Fig. 5, 18th bank contact and wiper in level 3 of the test control switch TC to earth at DC¹. Relay PR in operating, at PR¹ removes earth from contacts 22 to 25 in level P¹ of the release timing switch RT, Fig. 4, in order to permit the switch to stay off normal, at PR² opens the calling loop to the first code selector in order to start the release of the latter, and at PR² closes a circuit from the pulse conductor PC², cable 23, conductor 135, Fig. 4, PR², TC², CC², lower winding of two-step relay CC to battery. Upon the first earth pulse, the lower winding of relay CC energizes and at this time only closes contacts CC¹, thereby short-circuiting its upper winding by earth, RC¹, Fig. 4, RF¹, CC¹. At the end of the first earth pulse from the pulse conductor, the initial energizing earth is removed from the lower winding of relay CC. Relay CC now operates fully over both its windings in series from earth, RC¹, RF¹, CC¹, windings of relay CC in series to battery, and at CC² switches the pulse conductor PC² to the driving magnet DM⁶ of the release timing switch RT. Thus earth pulses at the rate of 20 per second are delivered to the driving magnet DM⁶ which advances the wipers of the release timing switch RT over their bank contacts at the rate of 20 steps per second.

When the first code selector releases owing to the opening of the loop earth is removed from the release trunk conductor and relay TC releases and places earth on the wiper of level 2 of the release timing switch by way of PR¹, TC¹, and conductor 136, and at TC² disconnects the 20 per second pulse conductor PC² from the driving magnet DM⁶. Should the release take place within the allowable limits, the release timing switch will be standing on one of contacts 8 to 13 and relay RC then operates from battery, winding of relay RC, conductor 137, contacts 8 to 13 of switch RT, wiper of release timing switch to earth. Relay RC in operating at RC¹ opens the circuit of relay CC which releases, at RC² places an earth on the 18th bank contact in level 4 of the test control

switch TC by way of conductor 138, RF², conductor 139, cable C²⁰, and conductor 139, Fig. 5, so that the driving magnet DM⁷ advances the wipers in the usual manner to the 19th position. Earth is now placed on the 19th bank contact in level 4 of the test control switch over RC², conductor 140, cable C²⁰, and conductor 140, Fig. 5, whereupon the driving magnet DM⁷ advances the wipers of the switch to the 20th position. In this position the fault lamp FL¹⁸ is lighted over conductor 112 to indicate that the release timing test has been successful. The test control switch in passing from position 19 to position 20 opens the circuit of relay PR which releases and at PR¹ removes earth from the wiper 2 of the release timing switch RT thereby opening the circuit of relay RC and also places earth on contacts 2 to 25 in level P of the release timing switch RT thereby operating driving magnet DM⁶ through its own interrupter springs to return the release timing switch to its home position. Relay RC in releasing places earth on the 20th bank contact of the test control switch over RC², conductor 141, cable C²⁰ and conductor 141, Fig. 5, and the driving magnet DM⁷ advances the switch to the 21st position.

Should the earth be removed from the release trunk conductor before the minimum permissible interval has elapsed, the release timing switch RT will be standing on one of contacts 2 to 7 and upon the release of relay TC relay RF will be operated from earth on wiper 2. In these circumstances no earth will be placed on the 18th bank contact in level 4 of test control switch and so the switch does not step. In this position fault lamp FL¹⁶ is lighted over conductor 110 to indicate that fast release has taken place and an alarm will be given after the usual three minutes delay.

Should the earth be removed from the release trunk conductor after the maximum permissible interval has elapsed the release timing switch RT will be standing on one of contacts 14 to 25 and relay RF will then be operated over its lower winding. Under these conditions an earth is placed on the 18th bank contact in level 4 of the test control switch TC by way of wiper 2 of the release timing switch, contacts 14 to 25, conductor 142, RF², and conductor 139, and the driving magnet DM⁷ accordingly advances the wipers of the test control switch to the 19th position. In this position fault lamp FL¹⁶ is extinguished and lamp FL¹⁷ is lighted over conductor 111 and to indicate that slow release has taken place and the alarm will again be given after a three minutes delay.

If all is in order however the test control switch is moved to position 21 and then closes a circuit to relay TM in order to effect the connecting up of the next first code selector

since the previous test has now been completed. Relay TM in operating at TM¹ opens the circuit of relay DB which releases, thereupon at DB⁵ opening the circuit of relay DC which releases also. Relay DC in releasing at DC² places an earth on bank contacts 2 to 25 in level P¹ of the sender switch SS so as to effect the restoration of the sender switch SS to its home position, at DC⁴ removes earth from the holding coil of the routine time check relay TC², Fig. 2, thereby causing it to release in preparation for routining the next first code selector, at DC⁵ places an earth by way of conductor 60, and cable C¹⁹ on contacts 2 to 4, 6 to 8, 10 to 12, 14 to 16, 18 to 20, 22 to 25 in level P¹ of the test switch TS, Fig. 6 so that driving magnet DM⁸ advances the test switch TS to its next home position. Relay DC moreover at DC¹ removes earth from wipers 2 and 3 of the test control switch TC and at its resting contact, places an earth over conductor 63 and cable C¹⁷ on contacts 2 to 25 in level P of test control switch TC whence it is extended over the wiper and interrupter springs to the winding of magnet DM⁷ so that the test control switch TC is rotated to the home position in known manner. Relay DB in releasing connects the 40 per minute pulse conductor PC¹ to the two-step relay DQ, Fig. 3, which operates in the manner previously described. Pulse conductor PC² is thus connected to relay DR, Fig. 3, which pulses at the rate of 40 per minute.

Upon the first operation of relay DR earth is connected to the driving magnet DM⁴ by the secondary distributor SW⁴ in order to step the latter to make connection with the next first code selector switch. The circuit extends from battery, DM⁴, conductor 42, 1st bank contact and wiper in level 7 of the primary distributor SW¹, Fig. 1, conductor 41, cable C⁶, conductor 41, Fig. 6, SA², conductor 40, SB², MB⁵, conductor 38, cable C²⁶, CR¹, conductor 37, cable C¹⁸, conductor 37, Fig. 3, DB², conductor 36, DS³, conductor 35, DR³ to earth, and magnet DM⁴ is operated preparatory to advancing the wipers. A circuit is also completed for the upper winding of two-step relay DB; battery, upper winding of relay DB, DB³, conductor 36, DS³, conductor 35, DR³ to earth, but at this time relay DB only operates its contacts DB⁴ thereby short-circuiting its lower winding by earth from TM¹, Fig. 5. At the end of the first relay DR releases, thereby removing earth from the driving magnet DM⁴ of the secondary distributor switch SW⁴ whereupon the wipers of the switch are advanced to the next set of contacts and make connection with the next first code selector switch to be tested. Relay DR also removes the earth from the junction of the windings of relay DB so that DB now operates over both its windings in series from earth at TM¹. Relay DB in operating, at DB¹ brings down two-step relay

DG so that no more pulses are delivered to relay DR, and at DB⁵ completes a circuit for relay DC which operates, and initiates the test cycle on the first code selector to which the secondary distributor is now connected. The secondary distributor, upon stepping will light lamp 2 of the switch lamps SL, Fig. 2, over conductor 143, thus indicating the switch in the shelf to which the connection has been made. Upon the completion of a successful routine test on this switch, relay TM will again be operated and will release relay DB as before described.

In this manner a complete shelf of 20 first code selector switches is routined and the secondary distributor switch SW⁴, Fig. 1 is then stepped from position 21 to position 22. In this position the circuit of relay LP through the switch indicating lamps SL, Fig. 2, and bank contacts 2 to 21 of the switch SW⁴ is opened and relay LP releases, thereupon opening the circuit of relay LS which releases also. Relay LS in releasing, at LS¹ opens the locking circuit of two-step relay DS which releases. Relay DB will also be released by TM operating after the completion of the test of the 20th switch in that shelf and closes a circuit for DQ and hence for relay DR as before described. Owing to the release of relay DS however, a circuit is now completed for advancing the first primary distributor to connect with the second secondary distributor. The initial operation of relay DR completes a circuit for the driving magnet DM¹ of the primary distributor SW¹ from battery, winding of magnet DM¹, conductor 144, cable C⁶, conductor 144, Fig. 6, DX¹, conductor 145, cable C²⁶, conductor 145, Fig. 5, CR³, conductor 146, cable C¹⁸, conductor 146, Fig. 3, DE¹, ST⁶, conductor 147, cable C¹⁸, conductor 147, Fig. 5, CR², conductor 148, cable C¹⁸, conductor 148, Fig. 3, DS³, conductor 35, DR³ to earth. Relay DR also at DR¹ closes a circuit for two-step relay DS from earth, conductor 149, ST⁵, DS¹, lower winding of relay DS to battery, and at DR² completes a circuit for relay DT, Fig. 3, which operates and locks up as previously explained. Relay DS at this time only operates its contacts DS², thereby short-circuiting its upper winding by earth from DT¹. At the end of the first pulse, relay DR releases thereby removing earth from the driving magnet DM¹ of the primary distributor SW¹ so that the wipers of the switch are moved to the second set of contacts thereby enabling the routiner to gain access to the next secondary distributor. The release of relay DR also removes the initial energizing earth from the two-step relay DS which now operates over both its windings in series from earth, DT¹, DS², windings of DS in series to battery. The next operation of relay DR over pulse conductor PC¹ at DR³ energizes the upper winding of two-step relay DB as previously explained.

Relay DR also at DR³ completes a circuit for the driving magnet of the next secondary distributor to which the primary distributor SW¹ is now connected extending from earth, 5 DR³, DS³, DB², conductor 37, cable C¹⁸, conductor 37, Fig. 5, CR¹, conductor 38, cable C²⁶, conductor 38, Fig. 6, MB⁵, conductor 39, SB², conductor 46, SA², conductor 41, cable C⁶, conductor 41, Fig. 1, wiper and second 10 bank contact in level 7 of the primary distributor SW¹ and driving magnet of secondary distributor (not shown) to battery. The driving magnet of this switch now energizes preparatory to stepping the wipers. Relay 15 DR releases upon the termination of the impulse and removes the initial energizing earth from relay DB which operates over both windings in series as previously explained. Moreover at DR³ the earth for the driving 20 magnet of the secondary distributor is removed and the wipers of this switch are stepped to the second set of contacts, so that the first code selector in the shelf is connected to the routiner. The primary distributor SW¹ in stepping to the second set of contacts disconnects bay and shelf lamp BSL¹, Fig. 2, and closes a circuit for the indicating lamp bay 1 shelf CD from battery, bay 1 shelf CD lamp, conductor 150, cable C¹¹, conductor 150, 25 Fig. 1, second bank contact in level 8 of the primary distributor SW¹, conductor 49, cable C⁶, SA¹, conductor 48, SB¹, conductor 47, cable C²⁶, conductor 47, Fig. 5, cable C¹⁸, conductor 47, Fig. 3, to earth at ST¹. The secondary distributor upon advancing to the second bank contact closes the circuit for relay LP, Fig. 4; battery, winding of relay LP, conductor 51, lamp SL, Fig. 2, conductor 52, cable C⁹, conductor 52, second bank contact and wiper in level P of the secondary distributor, interrupter springs, driving magnet to battery. Relay LP operates in this circuit 35 and lamp SL¹ glows but the driving magnet does not operate due to the resistance of lamp SL¹. Relay LP in operating completes a circuit for relay LS which operates as previously described.

The routine tests are now applied successively to the switches in the shelf served by 40 the secondary distributor with which the routiner is now connected. At the end of each complete test the secondary distributor will be stepped in order to connect to the next switch in the shelf as above described. The primary distributor will be stepped upon the completion of a successful routine test of any 45 particular shelf of first code selectors in the manner previously explained until all the first code selectors to which the primary distributor SW¹ has access have been routined.

In order that the routiner may connect with first code selector switches to which the second primary distributor SW¹ has access, the 50 25th bank contacts of levels 2 to 8 of the first primary distributor SW¹ are connected

through to the wipers of levels 2 to 8 of the second primary distributor SW², so that when the wipers of the switch SW¹ reach their 25th contacts the leads to the routiner are connected through to the second primary distributor SW². Moreover, relay DX is now operated from battery, winding of relay DX, conductor 158, cable C¹⁹, conductor 158, Fig. 3, SS¹, conductor 159, cable C⁷, conductor 159, Fig. 1, 25th bank contact and wiper in level P¹ of the primary distributor SW¹ to earth, and thereupon switches the pulsing circuit from the driving magnet DM¹ of the first primary distributor SW¹ to the driving magnet DM² of the second primary distributor SW². The circuit extends from battery, winding of driving magnet DM², conductor 151, DY¹, DX¹, conductor 145, cable C²⁶, conductor 145, Fig. 5, CR³, conductor 146, cable C¹⁸, conductor 146, Fig. 3, DE¹, ST⁶, conductor 147, cable C¹⁸, conductor 147, Fig. 5, CR², conductor 148, cable C¹⁸, conductor 148, Fig. 3, DS³, DR³ to earth. The first code selectors to which the second primary distributor SW² has access are routined in the manner previously described and the second primary distributor will finally step to the 25th position. In this position the leads from the routiner are switched through to the third primary distributor and relay 90 DY is also operated over the circuit battery, winding of relay DY, conductor 152, cable C¹⁹, conductor 152, Fig. 3, SS³, conductor 153, cable C⁷, conductor 153, Fig. 1, 25th bank contact and wiper of secondary distributor SW² to earth. The pulsing circuit thus prepared for the driving magnet DM³ of the third primary distributor SW³ is as follows:—battery, driving magnet DM³, conductor 154, DY¹, DX¹, conductor 145, cable 95 C²⁶ to earth at DR³, Fig. 3, over the circuit previously traced.

The first code selectors to which the primary distributor SW³ has access are routined in the manner previously described and in due course the primary distributor is stepped from position 19 to position 20. Since all the first code selector switches in the exchange have been tested, it is necessary to give a signal to indicate that the routining is 110 finished. This is done by relay SP which is now operated as follows:—battery, winding of relay SP, Fig. 6, conductor 155, cable C¹⁹, conductor 155, Fig. 3, SS⁵, conductor 156, cable C⁷, conductor 156, Fig. 1, contact 20 in level P of the third primary distributor SW³ and associated wiper to earth. Relay SP in operating, at SP¹ lights the routine finish lamp FL²⁰ from battery, lamp FL²⁰, conductor 113, SP² to earth, and at SP² operates relay PM from battery, lower winding of relay PM, conductor 157, cable C²¹, conductor 157, Fig. 6, SP¹ to earth. Relay PM is arranged to give an audible alarm which will notify 125

the attendant that the routining operation has been completed.

In order to restore the equipment to normal, the attendant releases the automatic start key AS whereupon the circuit for relay ST is opened and it releases and at ST¹ opens the circuit for relay SS which releases also. Relay SS in releasing closes circuit for relays ZA, ZB, ZC which relays operate and close restoring circuits to the magnets DM¹, DM² and DM³ of the primary distributors SW¹, SW², SW³. Relay ZA is operated at this time from battery, winding of relay ZA, conductor 160, cable C¹⁹, conductor 160, Fig. 3, SS¹, conductor 159 to earth at wiper P¹ of primary distributor SW¹ over the circuit previously traced and may also be operated over conductor 160, SS⁸, conductor 162, cable C⁷, conductor 162, Fig. 1, contacts 2 to 24 in level P¹ of the primary distributor SW¹ and associated wiper to earth. Relay ZB similarly is operated from battery, winding of relay ZB, conductor 161, cable C¹⁹, conductor 161, Fig. 3, SS³, conductor 153 to earth at wiper P¹ of primary distributor SW². Relay ZB may also be operated over conductor 161, SS¹, conductor 163, cable C⁷, conductor 163, Fig. 1, contacts 2 to 24 in level P¹ of the primary distributor SW², and associated wiper to earth. Relay ZC is operated from battery, winding of relay ZC, conductor 164, cable C¹⁹, conductor 164, Fig. 3, SS⁶, conductor 156 to earth at wiper P¹ of the third primary distributor SW³, and may also operate over conductor 164, SS⁶, conductor 165, cable C⁷, conductor 165, Fig. 1, contacts 2 to 19 in level P¹ of the third primary distributor SW³ and associated wiper to earth. Relays ZA, ZB, ZC in operating, at ZA¹, ZB¹, ZC¹, complete a circuit for relay PL over conductor 166, cable C²¹, conductor 166, Fig. 4, relay PL to battery, at ZA³, ZB³, ZC³ connect holding earth to relay DQ over conductor 167, cable C¹⁹, conductor 167, Fig. 3, in order to replace that removed by ST⁸, and at ZA², ZB², ZC² complete a circuit from the 40 per minute pulse conductor PC¹, cable C²³, conductor 22, Fig. 4, PM¹, conductor 168, cable C²¹, conductor 168, Fig. 6, ZA², ZB², and ZC² in parallel, conductor 169, cable C²¹, conductor 169, Fig. 4, conductor 70, cable C¹⁶, conductor 70, Fig. 3, DQ¹, conductor 24, DB¹, conductor 25, lower winding of relay DQ to battery. Hence pulses at the rate of 40 per minute are delivered to relay DQ and when this operates fully, to the relay DR which pulses in the manner previously described. A homing circuit for the primary distributor SW³ is now completed from battery, winding of magnet DM³, conductor 154, ZC⁴, conductor 170, cable C¹⁹, conductor 170, Fig. 3, ST⁶, conductor 147, cable C¹⁸, conductor 147, Fig. 5, CR², conductor 148, cable C¹⁸, conductor 148, Fig. 3, DS¹, conductor 35, DR³ to earth. Pulses of current are therefore fed to the driving magnet DM³ and the switch

SW³ is rotated to the home position. When this is reached, the circuit of relay ZC is opened and it releases and completes a homing circuit for the switch SW² as follows:—battery, winding of magnet DM², conductor 151, ZB⁴, ZC⁴, conductor 170, cable C¹⁹ to earth at DR³. When the switch SW² reaches normal position, relay ZB de-energizes and the following circuit is then completed for homing the first primary distributor; battery, winding of magnet DM¹, conductor 144, cable C⁶, conductor 144, Fig. 6, ZA⁴, ZB⁴, ZC⁴, conductor 170, cable C¹⁹ to earth at DR³, Fig. 3. Hence the switch SW¹ advances to its normal position whereupon relay ZA is de-energized. 80

Relay SS in releasing also opens the circuit of relays HA and HB which accordingly fall away. A homing earth through relay RAS is now placed on contacts 2 to 21 in level P of the secondary distributor SW⁴ by way of HA¹ and cable C¹⁰. The resistance of relay RAS is sufficiently low to permit driving magnet DM⁴ of secondary distributor SW⁴ to energize over its own interrupter springs IS⁴ and the switch SW⁴ is therefore rotated to the 22nd position. For advancing it from position 25 to its home position earth is supplied through relay RAS, conductor 171 to contacts 22 to 25 in level P of secondary distributor SW, and the switch SW⁴ is thus rotated to the 25 home position. Contacts 2 to 25 in level P of all the secondary distributors are multiplied together so that any secondary switches standing off-normal at this time will be rotated to home position by the circuits just described. 100

Relay PL in operating in response to the closure of its circuit as described above at PL² prepares a circuit for the primary release alarm lamp PRL, Fig. 2, and at PL¹ completes a circuit for the two-step relay TAR; earth, PL¹, conductor 172, normally closed contacts controlled by armature 1 of relay TAR, upper winding of relay TAR to battery, and also completes a circuit for the holding coil of the time check relay TC¹ from battery, lower winding of TC¹, conductor 173, cable C¹⁴, conductor 173, Fig. 4, normally closed contacts controlled by armature 1, relay TAR, conductor 172, PL¹ to 110 earth. Relay TAR at this time only operates its contacts TAR⁴, whereupon a circuit is closed from the pulse conductor PC³, cable C²⁷, conductor 174, PL³, TAR³, TAR⁴, conductor 175, cable C¹⁴, conductor 175, Fig. 120 2, upper winding of time check relay TC¹, resistance 176 to battery. Earth pulses are now delivered to the stepping magnet of the time check relay TC¹ at the rate of one pulse every two seconds. When the time check 125 relay operates in known manner, earth is extended to the lower winding of relay TAR to effect its full operation: battery, lower winding of relay TAR, conductor 177, cable C¹⁴, conductor 177, Fig. 2, TC³ to earth. Re- 130

lay TAR in operating, at TAR¹ completes locking circuit from battery, lower winding of relay TAR, armature 1 and working contact of TAR, conductor 172, PL¹ to earth, 5 at the same time opening the circuit to the holding coil of the time check relay TC¹ which therefore restores. Moreover relay TAR at TAR² opens the circuit to the stepping coil of the time check relay TC¹, at TAR⁵ closes 10 a circuit for an audible alarm over earth, TAR⁶, conductor 178, alarm bell to battery, and at TAR² closes a circuit for the primary release alarm lamp PRL: battery, PRL, conductor 179, cable C¹⁵, conductor 179, Fig. 3, 15 PL², TAR² to earth.

Relays RAS and RAR operate during the operation of the associated driving magnets and in operating RAS at RAS¹ closes a circuit for relay SL and RAR in operating 20 at RAR¹ closes a circuit for relay RL. Relays RL and SL in operating energize the lower winding of two-step relay TAR, which at this time only operates its contacts TAR⁴. The time check relay TC¹ is thus set in operation 25 as just described and an alarm is given after a time interval by the full operation of relay TAR. The various switches in the routiner will normally be rotated to their home position in ample time before the alarm 30 is given and when the stepping operation is completed the circuits for relays RAR, RAS and PL are opened. Relays RAR and RAS in releasing, bring down relays RL and SL and so disconnect the time check relay. By 35 this arrangement an alarm is only given when due to some unstandard condition the homing circuit of a switch is closed for a period longer than that necessary to return the switch to its normal position.

It may be desirable in certain circumstances 40 to be able to effect a repeated test of some particular switch and it will then be desirable to have some means for readily associating the routining equipment with any particular switch. In order to carry out a continuous routine test, the attendant first 45 throws the continuous routine key CRK, Fig. 2. A circuit is now completed for relay CR, Fig. 5, from battery, winding of relay 50 CR, conductor 180, cable C⁵, conductor 180, Fig. 2, contact CRK¹ to earth. Relay CR in operating at CR² disconnects the normal stepping circuit for the driving magnets DM¹, DM² and DM³ of the primary distributor 55 SW¹, SW², SW³, and at CR³ opens a point in the homing circuits and switches the driving magnet DM¹ of the switch SW¹ to the primary distributor stepping key PDSK, Fig. 2: battery, winding of DM¹, conductor 144, cable C⁶, conductor 144, Fig. 6, DX¹, conductor 145, cable C²⁶, conductor 145, Fig. 5, CR³, conductor 181, cable C⁵, conductor 181, Fig. 2, PDSK contacts 1 and 2 in parallel, conductor 182, AS² to earth. 65 Relay CR furthermore at CR¹ switches the

stepping circuit of the secondary distributor S to the secondary distributor stepping key SDSK, Fig. 2, at CR⁴ prepares a circuit for relay DY, at CR⁵ completes a circuit for relay SS from battery, winding of relay SS, Fig. 3, conductor 47, cable C¹⁵, conductor 47, Fig. 5, CR⁶ to earth, at CR⁶ prepares a circuit for relay DX, at CR⁷ prepares a circuit for relays SA and SB, Fig. 6, and at CR⁸ prepares a circuit for relay CB, Fig. 70 75 4. Relay SS in operating opens the homing circuit of the primary and secondary distributors as previously described. In order to save unnecessary rotation of the distributors SW¹ and SW², should the required 80 first code selector be associated with a succeeding primary distributor, circuits are provided for extending the wipers of primary distributor SW² and SW³ to the routining equipment independently of the preceding 85 distributor. Should the first code selector be accessible over primary distributor SW¹, distributor selecting key DSK Fig. 2 is left normal. If the first code selector is accessible over primary distributor SW², the distributor 90 selecting key DSK is thrown upwards in order to operate relay SA by means of which the wipers 2 to 8 of the primary distributor SW² are extended to the routiner independently of primary distributor SW¹. If the 95 first code selector is accessible over primary distributor SW³, the distributor selecting key DSK is thrown downwards in order to operate relay SB whereby the wipers 2 to 8 are extended to the routiner independently of the 100 primary distributors SW¹ and SW².

It will be assumed that the first code selector to which the continuous routine test is to be applied is associated with the third primary distributor SW³. In this case the distributor selecting key DSK is thrown downward in order to operate relay SB in the circuit: battery, winding of relay SB, conductor 183, cable C³, conductor 183, Fig. 2, DSK³, conductor 184, cable C⁵, conductor 184, Fig. 5, 110 CR⁷, conductor 185, cable C¹⁸, conductor 185, Fig. 3, relay SB to earth. Relay SB in operating at contacts SB¹⁻⁷ switches the leads from wipers 2-8 of the third primary distributor SW³ through to the routiner. Relay DX is 115 now operated in the circuit: battery, winding of relay DX, conductor 158, cable C¹⁸, conductor 158, Fig. 3, SS¹, conductor 186, cable C¹⁸, conductor 186, Fig. 5, CR⁶, conductor 187, cable C⁵, conductor 187, Fig. 2, key contacts 120 DSK⁴, conductor 184, cable C⁵ to earth at SS² over the circuit previously traced. Relay DY is operated from battery, winding of relay DY, conductor 152, cable C¹⁹, conductor 152, Fig. 3, SS³, conductor 188, cable C¹⁸, conductor 188, Fig. 5, CR⁴, conductor 189, cable C⁵, conductor 189, Fig. 2, key contacts DSK⁵, conductor 184, cable C⁵ to earth at SS². The 125 operation of relays DX and DY switches the pulsing lead to the magnet DM³ of the pri- 130

mary distributor SW³ through to the primary distributor stepping key. In order to step the third primary distributor SW³ on to the secondary distributor corresponding to the 5 bay and shelf in which the required first code selector is situated, primary distributor stepping key is operated until the requisite bay and shelf lamp BSL, Fig. 2, is lighted. In order to step the secondary distributor to 10 which connection has now been made, secondary distributor stepping key is operated until the switch lamp SL of the required switch in the shelf glows.

In order to set the routiner in operation, 15 the attendant now operates the automatic start key AS, whereupon a routine test will be started on the first code selector to which connection has been made. Upon the successful completion of this test the routiner cannot be stepped off this switch on the operation of 20 relay TM in the manner previously described, since relay CR is now operated and the automatic stepping circuits are opened. When the attendant key is thrown, the stepping earth is removed at contacts AS³ from the primary and secondary distributor stepping keys PDSK and SDSK in order to prevent the routiner being stepped off the required switch during progress of a continuous 25 routine test by the inadvertent operation of 30 either of these keys.

Suppose now that during the test of any switch the routiner finds a fault and accordingly the routine test stops and an alarm is 35 given to the exchange attendant after the usual delay period. The attendant by observing which of the fault indicating lamps FL is lighted can ascertain the nature of the fault encountered and can proceed to rectify it. When the fault is cleared it will be desirable 40 to have the routiner retest the switch on which the trouble occurred before proceeding with the testing of other switches. Accordingly the attendant now operates the re-set key RSK, Fig. 2, which causes the various 45 switches in the routiner to be rotated to their home positions and effects the release of the first code selector under test. The operation of the re-set key at RSK¹, removes earth from 50 DC¹ by way of conductor 65, cable C¹, from wipers 2 and 3 of the test control switch TC, Fig. 5, over the circuit previously traced and places earth on level P of the test control switch TC over conductor 190, Fig. 2, cable 55 C¹, conductor 191, Fig. 3, conductor 63, cable C¹⁷, conductor 63, Fig. 5, contacts 2 to 25 in level P of the test control switch TC, associated wiper, interrupter springs IS⁷, driving magnet DM⁷ to battery so that the test 60 control switch TC is rotated to the home position in known manner. At RSK² earth is placed on level P of test switch TC, Fig. 6, over conductor 191, cable C⁴, conductor 191, Fig. 6, to the multiplied contacts in the bank 65 of wiper P and said wiper, interrupter

springs IS⁸, driving magnet DM⁸ to battery so that the test switch TS is rotated to the home position, the test control switch in rotating to the home position will release the various relays operated from level 3 and thus 70 restore the routiner to normal. The test switch in rotating to the home position opens the loop to the first code selector under test and this switch releases. When the attendant releases the re-set key RSK, earth is removed from the P levels of the test control and test switches and is replaced on wipers 2 and 3 of the test control switch, Fig. 5. The routine test is thus re-started upon the switch on which the failure occurred and proceeds 80 in the manner previously described.

In order to enable the attendant to test the correct operation of the routiner itself, fault imitation keys have been provided, the operation of any one of which re-produces in the 85 routiner the same conditions as would the corresponding fault encountered on a first code selector during the progress of a test. The stopping of the routiner and the lighting of the proper fault indicating lamp is then an 90 indication of correct functioning.

The various fault imitation keys which have been provided are the test selecting key TSK, private disconnect key PDK, meter fail key MFK, negative test key NTK, and 95 positive test key PTK. The test selecting key TSK Fig 2 when operated upwards connects battery by way of resistance 192, springs TSK¹, conductor 77, to relays PP and PN Fig. 5. By the operation of the start key the routiner is started in normal manner and the connection of battery to conductor 77 by the operation of the test selecting key TSK is equivalent to the routiner being stepped upon an unequipped switch position. Relay PN should therefore operate and step the routiner to the next position. This condition will persist and therefore the routiner will continue to step until the test selecting key TSK is released. The test selecting key 100 when operated downwards places earth on conductor 77 providing a condition equivalent to the encountering of a busy switch by the routiner. Consequently the routiner will 105 now stop with fault lamp FL² lighted and after the delay period will give the usual alarm. This condition will persist until the test selecting key is released.

The operation of the private disconnect key PDK opens the circuit to the relay TC. 120 The routiner is started by means of the automatic start key as usual and the test proceeds on a first code selector until the private guard test is reached. Since TC cannot operate, the routiner should stop with fault lamp FL⁴ 125 lighted and in due course give the alarm. This test will indicate the correct functioning of the routiner for the private guard test.

The operation of meter fail key MFK Fig. 2 opens the circuit to relay TY. When the 130

5 routiner is started the test proceeds on a first code selector until the meter test is reached. The routiner should now stop with fault lamp FL¹⁵ lighted since earth placed on meter lead M, Fig. 1, is unable to operate relay TY. This operation will indicate the correct functioning of the routiner for the meter test.

10 The operation of the negative test key NTK upwards at NTK¹ places battery via resistance 193 on conductor 82 extending to the negative speaking conductor of the first code selector under test while the operation of the negative test key downwards at NTK² places 15 earth on the negative speaking conductor of the first code selector under test. After the routiner is started by the operation of the automatic start key AS it should stop with fault lamp FL³ lighted. If this duly takes 20 place, it will indicate the correct functioning of the routiner on the loop test.

25 The operation of the positive test key PTK upwards at PTK¹ places battery via resistance 194 on conductor 85, and hence on the positive speaking conductor of the first code selector, while the operation of positive test key downwards at PTK² places earth on the positive speaking conductor. The operation of this key in either direction should therefore stop the routine with fault lamp FL³ glowing. This will be a further test of the correct functioning of the routiner on the loop test.

30 Junction test key JNK is provided to place varying resistances in the lines from the calling loop of the first code selector to relay TT Fig. 6 so as to alter the characteristics of the circuit to the metering relay of the first code selector.

35 For performing tests manually, the manual start key MS has to be operated instead of the automatic start key AS. This will connect the negative and positive speaking conductors, the release trunk conductor, the K relay lead KR and the metering lead M to the first code selector under test, and also the lead to the driving magnet of the secondary distributor and the lead to the driving magnet of the primary distributor to multiply 40 connected 10-point test jacks MTJ, Fig. 6, located on each selector trunk board. The primary and secondary distributors can be stepped round by means of manual test set 45 plugged into any suitable manual test jack and thus connection made to any desired first code selector switch. The corresponding bay and shelf lamp BSL Fig. 2, and switch lamp SL Fig. 2 will be lighted on the routiner in the usual manner. By means of 50 a suitable manual test set a variety of tests can be made upon the first code selector and the attendant may if he wishes take up a position adjacent to the switch so as to watch its operation.

55 The only requirement in the manual test

set which is of any special nature is that the circuit must be so arranged that earth will be placed on the K relay lead to the first code selector under test before a loop is placed on the line relay. Thus relay K is operated without any hunting of the A digit switch selector which is therefore locked in the home position. This now connects the pulse lead to the manual test set to relay MC in the routiner which in turn repeats the impulses directly to the A relay of the first code selector. This enables the attendant to dial directly on to the A relay without using the A digit switch or register controller and all the principal features of the first code selector can thus be tested.

70 The operation of the manual start key MS Fig. 1 at MS¹ completes a circuit for relays MA and MB extending from battery, winding of relay MB, winding of relay MA, conductor 195, cable C⁴, conductor 195, Fig. 2, MS¹ to earth. Relays MA and MB operate in this circuit and relay MA at MA¹ places earth on wiper of level 8 of the first primary distributor SW¹ over conductor 196, SB¹, conductor 48, SA¹, conductor 49, cable C⁶ to wiper of level 8 of primary distributor SW¹, over the circuit previously traced. This earth will be connected to the bay and shelf lamp BSL Fig. 2 corresponding to the position to which primary distributors SW¹, SW², SW³ are stepped in the manner previously described. Relay MB in operating, at MB¹ 80 disconnects wiper of level 2 of primary distributor SW¹ from wiper 2 of the test switch TS and switches it by way of conductor 197 to terminal 198 and hence connects the negative speaking conductor of the first code selector to terminal 198 of the manual test jack, at MB² disconnects the lead from wiper 3 of the primary distributors SW¹ and switches it through by way of conductor 199 to terminal 200 and hence connects the positive speaking conductor of the first code selector to terminal 200 of the manual test jack, at MB³ disconnects the lead from wiper 4 of primary distributor SW¹ from the test switch level 4 and switches it through over conductor 201 to terminal 202 and hence connects the release trunk conductor of the first code selector through to terminal 202 to the manual test jack, and at MB⁴ disconnects the lead from wiper 5 of the primary distributor SW¹ from wiper 5 of the test switch TS Fig. 6 and switches it through over conductor 203 to terminal 204 and hence connects the K relay lead to the terminal 204 of the manual test jack. Furthermore relay MB at MB⁵ 90 disconnects the automatic pulsing circuit over conductor 38 and cable C²⁶ from relay DR over the circuit previously traced and switches it by way of conductor 205 and terminal 206 of the manual test jack, at MB⁶ disconnects the lead from wiper 6 of the primary distributor SW¹ from the test switch

130

TS and switches it through by way of conductor 207 and terminal 208 to the manual test jack, and thus connects the meter lead from the first code selector to the terminal 208 of the manual test jack, and at MB⁷ connects conductor 145 Fig. 8, and armature 1 of relay DX over conductor 209 to terminal 210 of the manual test jack. The earth placed on terminal 211 operates relay MC which thereupon at MC¹ places a loop across terminals 212 and 213 which are connected to the negative and positive lines at the home position of the A digit selector. Hence the operation of relay MC places the equivalent of the loop in the register controller across the first code selector. Impulses delivered to relay MC from the manual test set over terminal 214 will cause relay MC to impulse and at MC¹ to open the loop to the first code selector and thus impulses can be delivered directly for securing the operation of the first code selector instead of using the register controller. When using the manual test set, instead of stepping the preceding primary distributors to the 25th position in order to reach the first code selector associated with the succeeding primary distributor, the distributor selecting key may be used and hence by the operation of relays SA and SB the wipers to the required primary distributor are connected directly to the manual test set over relay MB.

What I claim as new and desire to secure by Letters Patent is:

1. In a telephone system, automatic routine testing equipment and manual routine testing equipment for testing selector switches, distributing switches for successively associating said selector switches with said testing equipments, and means for associating said distributor switches with either said automatic or said manual routine testing equipment.

2. In a telephone system, automatic routine testing equipment for testing selector switches, means for associating one of said selectors with said testing equipment, a line testing circuit extending from the line relay of said selector to marginal relays in said test equipment, means for testing said line for faults, and means responsive to an increase of current flow in said line due to a fault for operating said marginal relays to indicate the nature of said fault.

3. In a telephone system, automatic routine testing equipment for testing selector switches, means for associating one of said selector switches with said testing equipment, a line testing circuit extending from the line relay of said selector switch to a normally balanced Wheatstone bridge in said testing equipment, a polarized relay connected across the neutral points of said bridge, and means controlled by a fault in said line circuit for operating said polarized relay to indicate the nature of said fault.

4. In a telephone system, automatic routine testing equipment and manual routine testing equipment for testing selector switches, means for associating said selector switches with either of said testing equipments, means responsive to the connection of said selector switches with said automatic routine testing equipment for sending impulses to operate a register controller switch to control said selector switches, and means responsive to the connection of said selector switches with said manual routine testing equipment for sending impulses direct to said selector switches and prevent said register switch from operating.

5. In a telephone system, automatic routine testing equipment and manual routine testing equipment for testing selector switches, means for associating said selector switches with either of said testing equipments, means responsive to the connection of said selector switches with said automatic testing equipment for sending impulses to operate a register controller switch to control said selector switches, means responsive to the connection of said selector switches with said manual testing equipment for sending impulses direct to said selector switches, a switch in either type of said connections for seizing said register controller, said switch having a normal position to which no register controller is connected, and means responsive to the connection of said manual testing equipment with said selector switches for locking said switch in said normal position and extending the connection over the wipers of said switch in normal position.

6. In a telephone system, automatic routine testing equipment and manual routine testing equipment for testing selector switches, distributor switches for successively associating said selector switches with either of said testing equipments, test contacts in the banks of said distributor switches associated with the test leads of said selector switches, means responsive to the engagement of said selectors for applying earth potential to said test contacts, means responsive thereto if no test is to be made for applying battery potential to said test contacts, and means responsive to either of said potentials for operating a set of polarized relays for effecting circuit changes over said test lead.

7. In a telephone system, automatic routine testing equipment and manual routine testing equipment for testing selector switches, distributor switches for successively associating said selector switches with said testing equipments, means for associating said distributor switches with either of said testing equipments, a test jack associated with the wipers and controlling leads of said distributing switches, and means for connecting said wipers and controlling leads over said test jack with said manual testing equipment.

8. In a telephone system, automatic routine testing equipment and manual routine testing equipment for testing selector switches, primary and secondary distributor switches for successively associating said selector switches with said testing equipments, and a plurality of contacts in the banks of said primary distributor switches, said contacts all connected except the last ones to the wipers of said secondary distributor switches and said last contacts connected to the wipers of the succeeding one of said primary distributor switches.

9. In a telephone system, automatic routine testing equipment for testing selector switches, primary and secondary distributor switches for successively associating said selector switches with said testing equipment, a control key having a normal and operated position for controlling the connecting up of one of said primary distributor switches, and a stepping key for advancing said primary distributor dependent on the position of said control key.

10. In a telephone system, automatic routine testing equipment for testing selector switches, a primary distributor switch connected to said testing equipment, secondary distributor switches connected to said primary distributor switch for successively associating said selector switches with said testing equipment, a control key having a normal and operated position, and a stepping key for advancing said primary distributor switch step by step when said control key is in normal position.

11. In a telephone system, automatic routine testing equipment for testing selector switches, a primary distributor switch connected to said testing equipment, secondary distributor switches connected to said primary distributor switches for successively associating said selector switches with said selector switches, a plurality of contacts in the banks of said primary distributor switches, said contacts all connected except the last ones to the wipers of said secondary distributor switches and said last contacts connected to the wipers of the succeeding one of said primary distributor switches, a control key for controlling the connecting up of said primary distributor switch, and means controlled by said control key for connecting the wipers of said primary distributor switch directly to said testing equipment independent of said last contacts in the banks of said preceding primary distributor.

12. In a telephone system, automatic routine testing equipment and manual routine testing equipment for testing selector switches, primary and secondary distributor switches for successively associating said selector switches with said testing equipments, a plurality of contacts in the banks of said

primary distributor switches, connected except for the last ones to the wipers of said secondary distributor switches, said last contacts connected to the succeeding one of said primary distributor switches, and a relay energized from an off-normal bank of said primary distributor switches for connecting up a source of impulses to the driving magnet of said primary distributor for restoring said switch to normal position.

13. In a telephone system, automatic routine testing equipment and manual routine testing equipment for testing selector switches, means for associating one of said selector switches with said automatic testing equipment, a rotary switch in said testing equipment, means controlled by said rotary switch for applying a plurality of tests of similar character but different effect to said selector switches, means for advancing said rotary switch upon the completion of one test to initiate the succeeding test, and an impulse responding relay in said selector switch tested by said test equipment in circuits of different electrical characteristics.

14. In a telephone system, automatic routine testing equipment for testing selector switches, means for temporarily associating said selector switches with said testing equipment, means for automatically releasing said selector switches after a time interval, a register controller associated with said selector switches and accessible to said testing equipment, means for automatically releasing said register controller after a time interval, and means in said testing equipment for testing the said said release of said selector switches and said register controller.

15. In a telephone system, automatic routine testing equipment for testing selector switches, means for associating one of said selector switches with said testing equipment or with its normal means of access, means for routine testing said selector a plurality of times in succession, means for busying said selector to said normal means of access while said testing equipment is preparing for a succeeding test thereon, a relay held energized by said busying means, and means responsive to the deenergization of said relay for bringing in a signal and to energize another relay to re-apply said busying means to said selector switch.

16. In a telephone system, separate automatic routine testing equipment and manual routine testing equipment for testing selector switches, distributing switches for successively associating said selector switches with said testing equipments, and means for associating said distributor switches with said automatic routine testing equipment and disconnecting said manual routine testing equipment to perform a plurality of tests automatically on said selectors.

17. In a telephone system, separate auto-

matic routine testing equipment and manual routine testing equipment for testing selector switches, distributing switches for successively associating said selector switches with said testing equipments, and means for associating said distributor switches with said manual routine testing equipment and disconnecting said automatic routine testing equipment to perform a plurality of tests manually on said selectors.

18. In a telephone system, automatic routine testing equipment for testing telephone apparatus, means for associating said equipment with one piece of apparatus to perform a series of functional tests thereon, and means in said testing equipment to simulate unstandard conditions to cause the piece of apparatus being tested to test said testing equipment.

20. In testimony whereof I have signed my name this 2nd day of September, 1927, at London, England.

JOHN ELLIS OSTLINE.
